E. L. RICHARDSON

TURBINE INSTALLATION

Filed March 6, 1924

Inventor:
Ernest L. Richardson,
by Alexander S. Kline,
His Attorney.

UNITED STATES PATENT OFFICE.

ERNEST L. RICHARDSON, OF MELROSE HIGHLANDS, MASSACHUSETTS, ASSIGNOR TO
GENERAL ELECTRIC COMPANY, A CORPORATION OF NEW YORK.

TURBINE INSTALLATION.

Application filed March 6, 1924. Serial No. 697,402.

The present invention relates to turbine installations wherein the feed water for the boilers, which feed water comprises the condensate from the condenser of the main turbine, is heated to the desired temperature by steam taken from some source of low pressure supply such as for example, the exhaust from a non-condensing auxiliary turbine, the supply of heating steam being regulated 10 in accordance with the requirements for heating steam.

The object of the invention is to provide an improved construction and arrangement for regulating the auxiliary steam supply in 15 accordance with the heating requirements, and for a consideration of what I believe to be novel and my invention, attention is directed to the accompanying description and the claims appended thereto.

20 In the drawing, Fig. 1 is a diagrammatic view of an installation embodying my invention, and Fig. 2 is a detail thereof in cross-section, on a greatly enlarged scale.

Referring to the drawing, 1 indicates a 25 condensing steam turbine which receives steam from a main 2 through a conduit 3 and exhausts into a condenser 4. Main 2 may be supplied with steam from a suitable boiler or boilers. 5 indicates the hot well 30 of the condenser from which the water is withdrawn by a pump 6 through a conduit 7 and discharged through a conduit 8 to a suitable heater 9 which is supplied with heating steam from a low pressure stage of 35 turbine 1 by a conduit 10. From heater 9 the water flows through a conduit 11 to a heater 12 which is shown as being of the closed type, and after being heated in heater 12 it is discharged through a conduit 13 to 40 a storage tank 14 from which it may be fed back to the boiler (not shown) through a pipe 15.

Heating steam for heater 12 is supplied 45 through a conduit 16 and in the present instance is shown as being supplied by the exhaust from a non-condensing turbine 17. Turbine 17 is supplied with steam from main 2 through a conduit 18 and has its exhaust opening connected directly to conduit 16. The flow of steam through conduit 18 to turbine 17 is controlled by a valve 19 operated by a servo-motor 20 which is connected to a speed governor 21. The governor is provided with a synchronizing 50 spring 22 which is adjusted by a motor 23.

This governor and valve arrangement indicated in the drawing is a well known one, the operation of which is well understood.

In the present instance turbine 17 is shown as being a part of three unit exciter 60 set, 24 being the exciter of the set and 25 the motor of the set. However, the turbine may drive any suitable load. In an arrangement of this character, the steam supplied through conduit 16 to heater 12 is regulated 65 by regulating the amount of steam supplied to the turbine, only sufficient steam being supplied to turbine 17 to meet the requirements for heating steam. The condensate from heater 12 collects in a well 26 and may 70 be supplied through a conduit 27 to the inlet of heater 9, a pump 28 being used if required.

My invention relates especially to the 75 regulating of the supply of heating steam through conduit 16 to heater 12 so as to maintain an even heating of the water and according to my invention, I regulate the supply of heating steam in accordance with the pressure of the steam being supplied for 80 heating purposes and the temperature of the heated water as it flows from the heater, the arrangement being such that the supply of heating steam can be increased only when there is a decrease in both the pressure of the 85 heating steam supply and the temperature of the water leaving the heater and that the supply of heating steam can be decreased only when there is an increase in both the pressure of the heating steam supply and the 90 temperature of the water leaving the heater. By this means I am enabled to maintain a more even heating of the water and prevent wide, repeated fluctuations of the steam supply. 95

In the arrangement illustrated in the drawing, 29, and 30 are two pairs of spaced contacts adapted to be bridged by a connector 31 attached to a pressure responsive device 32 which is connected to conduit 16 100 by a pipe 33. Pressure responsive device 32 may be of the well-known form comprising a diaphragm contained in a casing and upon which the pressure acts, the arrangement being such that upon an increase in 105 pressure connector 31 will be raised to bridge contacts 29 and upon a decrease in pressure connector 31 will be lowered to bridge contacts 30. At 34 and 35 are two pairs of spaced contacts adapted to be bridged by a 110

connector 36 attached to a temperature responsive device 37 arranged to respond to the temperature of the heated water flowing from heater 12, the arrangement being such 5 that upon an increase in temperature connector 36 will be raised to bridge contacts 34 and upon a decrease in temperature it will be lowered to bridge contacts 35. Any suitable type of temperature responsive device 10 may be used, a known type comprising a diaphragm 38 moved by the expansion of a liquid contained in it and in its connecting tube 39 which has a closed end 41 located in conduit 18 where it is exposed to the temperature of the water flowing through the conduit, as shown in Fig. 2.

Contacts 29 and 34 are connected in series with each other and to motor 23 and a suitable source of potential 40 in such manner 20 that when contacts 29 and 34 are bridged by connectors 31 and 36 respectively a circuit is closed through motor 23 to effect its operation in a direction to close somewhat valve 19 thus causing a decrease in the supply 25 of heating steam, and contacts 30 and 35 are connected in series with each other and to motor 23 and source of potential 40 in such manner that when they are bridged by connectors 31 and 36 a circuit is closed 30 through motor 23 to effect its operation in a direction to open somewhat valve 19 thus providing an increase in the supply of heating steam.

In use, the temperature contacts 34 and 35 are set for the desired temperature range 35 so that when the temperature of the feed water from heater 12 reaches the upper limit of its range connector 36 bridges contacts 34 and when the temperature reaches the lower 40 limit connector 36 bridges contacts 35. Contacts 29 and 30 are then set so that with a supply of heating steam which will heat the feed water in heater 12 to the upper temperature limit, the pressure in conduit 16 will hold connector 31 in engagement with contacts 29, and with a supply of heating steam which will heat the water to the lower temperature limit the pressure in conduit 16 will be such that connector 31 will bridge 45 contacts 30.

Assume now that the main turbine unit 1 and auxiliary turbine unit 17 are started and condensate from condenser 4 enters heater 12 at a low temperature. Under these 50 conditions connector 31 will bridge contacts 30 due to the fact that the rate of absorption in heater 12 will be so rapid that the pressure in conduit 16 cannot build up to the lower pressure limit. At the same time connector 36 bridges contacts 35 because of the low temperature of the water leaving heater 12. A circuit is thus closed through motor 23 to cause it to operate on the valve gear in a direction to effect the opening of valve 19, thus increasing the supply of heating steam 55

supplied through conduit 16. Valve 19 will be fully opened and will remain open until the water in heater 12 heats up to the point where the flow of steam provides heat faster than it can be absorbed whereupon the pressure in conduit 16 will increase causing connector 31 to move from engagement with contacts 30 into engagement with contacts 29. Following this, the temperature reaches a value at which connector 36 will be moved 60 from engagement with contacts 35 to engagement with contacts 34 thus completing the circuit on motor 23 to operate it in a direction to move valve 19 toward closed position. Valve 19 will be then moved toward the closed position until it reaches a point where the pressure in conduit 16 drops below the high value for which contacts 29 are set whereupon connector 31 will move away from contacts 29 and open the circuit 65 on motor 23. A balanced condition is thus established at which the water in heater 12 is heated to the desired temperature. Whenever a balanced condition is disturbed, a thing which may be caused by an increase 70 or a decrease in the amount of water to be heated due to change in load on turbine 1, then the same general cycle of operation or its reverse is repeated to again restore the balance. 75

With the above described arrangement it will be seen that when the circuit is closed on motor 23 by the temperature responsive device 37 cooperating with the pressure responsive device 32, such circuit does not remain closed until the temperature change required is registered on the temperature responsive device by the outflowing water, but is opened as soon as the pressure of the heating steam reaches normal value again. 80 By this means the opening of the circuit is rendered independent of the heat capacity of the heater. This renders the temperature control more sensitive because it responds more quickly to changes in the supply of 85 heating steam thus preventing changes in temperature producing correspondingly too great changes in the supply of heating steam and hence what may be termed hunting of the control means for the heating steam supply and wide fluctuations of the temperature of the water. 90

What I claim as new and desire to secure by Letters Patent of the United States, is:

1. In an apparatus of the character described, the combination of a heater, means for supplying liquid thereto to be heated, means for supplying heating elastic fluid thereto, and means responsive to the pressure of the heating elastic fluid and the temperature of the liquid leaving the heater for controlling the supply of heating elastic fluid. 100

2. In combination, a condensing turbine, a heater, means for conveying condensate from the turbine to the heater, a conduit for 105

- supplying heating elastic fluid to the heater, a valve means controlling the flow of heating elastic fluid through such conduit, and means responsive to both the temperature of the water leaving the heater and the pressure of the elastic fluid supplied thereto for controlling said valve means.
3. In combination, a condensing turbine, a heater, means for conveying condensate from the turbine to the heater, a conduit for supplying heating elastic fluid to the heater, a non-condensing turbine, means for conveying the exhaust from it to the heater to heat the condensate, a valve gear controlling the admission of elastic fluid to the turbine, and means responsive to the temperature of the condensate flowing from the heater and the pressure of the exhaust from the non-condensing turbine for controlling said valve gear.
4. In an apparatus of the character described, the combination of a heater, a conduit for supplying liquid thereto to be heated, a conduit for supplying elastic fluid to the heater to heat the liquid, a valve means controlling the flow of elastic fluid through the last named conduit, means for moving said valve means toward the closed position when both the temperature of the liquid flowing from the heater and the pressure of the elastic fluid supplied to the heater reach predetermined high values, and means for moving said valve means toward the open position when both the temperature of the liquid flowing from the heater and the pressure of the elastic fluid supplied to the heater reach predetermined low values.
5. In an apparatus of the character described, the combination of a heater, a conduit for supplying liquid thereto to be heated, a conduit supplying elastic fluid to the heater to heat the liquid, a valve means controlling the flow of elastic fluid through the last named conduit, an electric motor operatively connected with the valve means for moving the same, an electric circuit for the motor which when closed operates the motor in a direction to open the valve means, a second electric circuit for the motor which when closed operates the motor in a direction to close said valve means, means for closing the first-named circuit when both the temperature of the liquid leaving the heater and the pressure of the elastic fluid supplied to the heater reach predetermined low values, and means for closing said second-named circuit when the temperature of the liquid leaving the heater and the pressure of the elastic fluid supplied to the heater reach predetermined high values.
6. In an apparatus of the character described, the combination of a heater, means for supplying thereto a liquid to be heated, a discharge conduit connected with the heater through which heated liquid flows, a conduit connected with the heater through which heating elastic fluid is supplied to said heater, a temperature responsive device connected with the discharge conduit of the heater, said device having a member which moves in response to temperature changes in the heated fluid, a pressure responsive device connected with the heating elastic fluid supply conduit, said device having a member which moves in response to pressure changes in the heating elastic fluid, and control means for the heating elastic fluid connected with and jointly operated by the movable members of said temperature and pressure responsive devices, said control means operating to reduce the flow of heating elastic fluid when the temperature and pressure simultaneously attain certain predetermined high limit values and to increase the flow of said elastic fluid when the temperature and pressure simultaneously attain certain predetermined low limit values.
7. The combination with a liquid heater having a discharge conduit through which a heated liquid flows, of an elastic fluid turbine having an exhaust outlet conduit connected with said heater to supply thereto exhaust elastic fluid as a heating medium, a valve gear controlling the admission of elastic fluid to the turbine, an operating governor for the turbine controlling said valve gear, said governor being adjustable to effect through the valve gear an increase and decrease in the flow of elastic fluid to the turbine, an electric motor by which the governor is adjusted, an electrical circuit for the motor which, when closed, operates said motor in a direction to cause an increase in the flow of elastic fluid to the turbine, a second electrical circuit for the motor which when closed operates said motor in a direction to cause a decrease in the flow of elastic fluid to the turbine, means responsive to the pressure in the exhaust outlet conduit and to the temperature in the heater discharge conduit for closing the first named circuit when said pressure and temperature both reach predetermined low values and for closing the second named circuit when said pressure and temperature both reach certain predetermined high values.

In witness wherof, I have hereunto set my hand this 4th day of March 1924.

ERNEST L. RICHARDSON.
